(57) **CLAIM**

The ornamental design for an abrasive material, as shown and described.

DESCRIPTION

FIG. 1 is a top plan view of a first embodiment of an abrasive material, showing one repeat unit of our new design with granules. The design can be repeated in any direction.

FIG. 2 is a right side elevational view thereof. The left side elevational view is a mirror image thereof.

FIG. 3 is a front elevational view thereof. The rear elevational view is identical thereto.

FIG. 4 is a bottom plan view thereof.

FIG. 5 is a top perspective view thereof.

FIG. 6 is a bottom perspective view thereof; and,

FIG. 7 is a perspective view, showing the repeat unit as part of a larger piece of abrasive material.

The broken dot-dash lines in the views define the peripheral boundaries of one repeat unit of the claimed design and are not part of the claimed design. The evenly broken dash-dot lines are used to depict environmental features for illustrative purposes only and form no part of the claimed design.
